TARGET DEVICE

Walter A. Tratsch, Chicago, Ill.

Application January 17, 1941, Serial No. 374,806

1 Claim. (Cl. 273—105.2)

This invention relates to certain novel improvements in target devices and has for its principal object the provision of an improved construction of this character which will be highly efficient in use and economical in manufacture.

Among the salient objects of the present invention is the provision of a combination and arrangement of parts for removably presenting a target to the marksman in a manner such that when the target is struck by the pellet the same can freely move from target-supporting position for return by a return mechanism to target-moving position into and through the aiming range of the device.

A still further object of the invention resides in the novel and inexpensive arrangement for recording hits scored by the marksman.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective front elevational view of the target apparatus embodying my invention;

Fig. 2 is a fragmentary sectional detail view of the same taken substantially on lines 2—2 of Fig. 1;

Fig. 3 is a fragmentary sectional detail view of the same taken substantially on lines 3—3 of Fig. 2;

Fig. 4 is a fragmentary sectional detail view of the upper portion of the target return mechanism; and

Fig. 5 is a fragmentary perspective view of the target conveyor.

In the drawings I have illustrated the preferred form of construction of my invention. In this connection the target apparatus comprises a box-like structure 10 having side walls 11 between which is arranged a rearwardly and downwardly extending target wall 12 having its target face 13 covered with a pellet-resisting material 14 preferably of a metal suitable for that purpose. In this target wall 12 with edges 15 likewise lined with pellet-resisting material, are inclined elongated openings 16, arranged with an intermediate elongated opening 17 inclined at an angular position with respect to the two openings 16. The target wall 12, together with runways 19 disposed along the lower edge 18 of the openings 16 and 17, serves to movably support the target elements 20, which in the present instance are

formed disc-like and of a metal which is adapted to resist the impact of pellets striking against these targets. These runways 19 are so arranged with respect to each other that the target will travel over the target wall to the rear thereof in zig-zag formation. These discs 20 are conveyed to the uppermost of the runways 19 by a motor-driven conveyor belt 21 having disposed at intervals on the face thereof target-supporting steps 22 whereby the targets delivered, in a manner hereinafter explained, to the elevator will by these steps be brought to the uppermost of the runways 19 and, by virtue of the inclination of these steps with respect to the conveyor belt 21, the targets will roll by gravity onto the uppermost of the runways 19 for travel therealong with portions thereof exposed through the openings 16 and 17.

In the present instance this conveyor belt is supported by opposite pulleys 22', one of which is driven by a suitable motor 23.

Associated with the target wall 12 to the rear thereof is an inclined platform 24 onto which the targets 20 are adapted to drop when unseated from the runways 19 upon being struck by the pellets. As these targets 20 drop upon this platform 24, by virtue of the inclination of this platform 24 the targets will slide downwardly into a trough-like structure 25 onto a conveying chain 26 driven by a suitable motor 27 and having a suitable tensioning device 28. As these targets 20 drop upon this conveyor chain 26, they are conveyed for passage through an opening 29 onto the elevator within which the conveying belt 21 is arranged, whereupon the target will be seated upon one of the inclined steps 22 for elevation up to the uppermost of the runways 19.

In their movement from the platform 24 into the trough structure 25, the targets come into contact with an elongated strip 30 pivotally supported on the target wall as at 31 and having associated therewith a contact closing pin 32 bearing against a spring contact leaf 34 whereby the weight of the target against the strip 31 will cause the pin 32 to bear against the spring contact leaf 34, bringing the same into contact with a companion spring contact leaf 35 to complete a circuit to a score relay 36 of a well-known type, whereby to register a score in a manner well-known in the art.

As shown in Fig. 3, the discharge end 37 of the conveyor 26 is disposed in spaced relation with respect to the conveyor chute 21' in which the conveyor belt 21 is positioned, so that any pellets passing through the openings 16 and 17

and finding lodgement on the platform 24 will gravitate into the trough structure 25 onto the conveyor chain 26 and be thereby conveyed for gravitation into a pellet-receiving receptacle 38 removably associated with the target device.

By inclining the target wall 12, it is obvious that the weight of the targets 20 will bear against this wall and be exposed through the openings 16 and 17 while gravitating down the runways 19 and when struck by a pellet it will be apparent that there is nothing to interfere with the target being unseated from the runways 19 to fall upon the platform 24, where they are gravitated into contact with the strip 30 for reasons herein explained, and hence onto the conveyor chain 26 for passage to the conveyor 21 to be conveyed thereby into position where by the action of an ejector spring 39 the target discs will be ejected onto the uppermost of the runways 19.

While I have illustrated and described the preferred form of construction for carrying my invention into effect, this is capable of variation

and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

10 In a target apparatus for rolling disc targets, a target range comprising a downwardly and rearwardly inclined target wall having one or more inclined elongated openings formed therein, inclined runways to the rear of said wall and adjacent the lower elongated edge of said openings and adapted with the cooperation of said target wall to support rolling disc target elements for gravitation theredown while exposed through said openings whereby the target elements may be unseated from said runway at any point along the latter when struck by a pellet.

WALTER A. TRATSCH.
